UNITED STATES PATENT OFFICE

IVAR E. SIQVELAND, OF ST. PAUL, MINNESOTA

DENTAL ROLL DISPENSER

Application filed April 16, 1931. Serial No. 530,485.

The present invention relates to a dispensing mechanism and more particularly to a mechanism for dispensing cylindrical objects, such as rolls of absorbent cotton, such as are used by dentists.

At present dentists keep their cotton rolls, which are usually cut into short lengths for convenient use in a patient's mouth, in a drawer or in a glass jar, and, when it is desired to use a roll, the roll is picked from the drawer or the jar either with the tweezers or with the fingers. This leaves the rolls exposed to the air and also presents the possibility of contamination of other rolls by touching them with the tweezers or fingers which have been in the patient's mouth.

An object of the present invention is to make an improved and simplified dispensing mechanism.

20 In order to attain this object, there is provided, in accordance with one feature of the invention, a container adapted to hold a quantity of articles to be dispensed, said container having an aperture of a size to permit the discharge of one of the articles therethrough. This aperture is normally closed by a member which is arranged to be moved away from the opening upon operation of the mechanism and a pusher is arranged to be operated simultaneously with the removal of the closure from the opening to eject one of the articles through said opening.

These and other features of the invention will be more fully brought out in the following description and the accompanying drawing, wherein:

Figure 1 is a view in perspective of a mechanism embodying the present invention.

40 Figure 2 is a vertical, longitudinal view through the mechanism shown in Figure 1, the solid lines indicating the parts in an unoperated position, and the dotted lines indicating the parts in operated condition.

45 Figure 3 is a view in front elevation of a combined ejector lever and closure member.

Figure 4 is a view in front elevation of a combined ejector and agitating member.

Figure 5 is a view in front elevation of a door.

50 Figure 6 is an enlarged sectional view of a

lower rear corner of a size of the housing showing a slot for holding the ejector lever in position.

Figure 7 is a still further enlarged view in perspective of a slotted member illustrated in Figure 6; and

Figure 8 is a top view showing one-half of the ejector lever illustrated in Figure 3.

Referring to the drawing in detail, a housing A comprises similar side members 1 with a back plate 2 having a curved upper portion 3 permanently secured to said side members. The lower edges 4 of the side members are bent inwardly and are secured to a base member 5 as by means of bolts 6. A door 7 is provided with a sight opening 8 which is preferably covered on its rear face by a transparent closure member 9 such as glass or celluloid. This transparent closure member is held in place by means of clips 10 secured to the rear face of the door. A curved metal plate 11 is securely and permanently mounted across the inner face of the lower edge of the door and acts as a cam to prevent the rolls from jamming upon actuation of the mechanism. Tongues 12 and 13 extend downwardly from the two sides of the door, the sides 14 of which are bent at right angles to the face of the door to form overlapping flanges which overlap the forward edges of the side walls of the housing A. Pins 15 pivotally secure the door to the housing so that the door may be swung outwardly for the insertion of a fresh supply of rolls into the housing. The door 7 is mounted with its lower edge spaced upwardly from a bottom plate 16 of the housing A a sufficient distance to permit a roll to pass between the lower edge of the door and the bottom plate. A curved plate 17, preferably of spring material, is mounted as illustrated in Figure 2, the forward upper edge of the curved plate 17 being bent downwardly as at 18 to engage the side of a nut 19. An adjusting screw 20 is threadedly connected to the nut 19 and by means of the screws 20 and the nut 19 the tension on the spring plate 17 may be adjusted. The lower end of the spring plate 17 is rounded and extended rearwardly as at 21.

This lower portion of the spring plate 17

forms an ejector for ejecting a roll through the opening between the lower edge of the door 7 and the bottom plate 16. A combined ejector lever and closure member B has a substantially vertical rear portion 22, a horizontal lower portion 23, and an upwardly bent portion 24 which forms a closure over the ejection opening, below the door 7. An operating key 25 is connected to extend forwardly from the portion 24 and two curved portions 26 and 27 are provided to receive a roll upon ejection and to permit seizing the roll by its center as by means of tweezers or the fingers. The member B is provided with a pair of projections 28 and 29 at the angle between the vertical rear portion 22 and the horizontal portion 23. A pair of slotted members 30 are permanently secured to the lower rear corners of the side members 1 as by brazing. It will be noted that the permanent bottom portion 16 of the container terminates short of the rear wall 2 of the container so as to permit inserting the vertical rear portion 22 of the ejector lever therein. The ejector lever is placed with the vertical rear portion 22 thereof in this slotted opening and is raised up so that the pins 28 and 29 enter the slots in the members 30. When the pins 28 and 29 reach the tops of the vertical portions of the slots, the member B is moved rearwardly, moving the pins 28 and 29 along the upper horizontal portion of the slots and dropping them into the notched rear portion 31 of these slots. In operation of the device, the pressure is rearwardly on these pins so that there is no tendency for them to become displaced. The horizontal portion 23 of the member B is cut away at the sides thereof, as illustrated in Figure 8, to avoid striking the inturned edges 4 on the bottoms of the side walls.

In operation of the device, the door 7 is opened and a quantity of rolls to be dispensed are placed in the interior of the container A in horizontal, transverse position. The door 7 is then closed. The operator by placing a finger 32 indicated in dotted lines in Figure 2, upon the operating key 25, depresses the ejector lever to the dotted line position shown in Figure 2. It will be noted that some clearance is provided between the rounded forward lower portion 21 of the spring plate 22 and a roll 33 to be ejected. This is required, since the ejector lever B starts the spring plate 22 forward immediately upon starting depression of the ejector lever. The vertical portion 24 of the ejector lever does not, however, immediately clear the opening. It is preferable that the rounded forward portion 21 of the spring plate 22 engages the roll 23 slightly before the vertical portion 24 clears the ejection opening sufficiently to discharge the roll, so that when the vertical portion 24 does clear the opening a slight spring pressure will be present against the roll. In this

manner when the vertical portion 24 clears the opening, the roll will be ejected sharply into the troughed portion provided by the portions 26 and 27. The curved forward portion 21 of the spring plate 22 acts as a cam to raise any roll not in position for ejection out of position. The cam plate 11 acts to support the rolls above the one to be dispensed to prevent jamming with said roll. Upon operation of the device it will be noted that the vertical rear portion of the spring plate 22 is moved forward and this acts to agitate the remaining rolls in the container. When the plate 22 returns to its normal, solid line position, as shown in Figure 2, the rolls drop into a new position, the lowermost roll dropping into position for ejection upon the next operation of the mechanism. This agitation of the rolls upon each operation of the device is particularly desirable for the cotton rolls herein referred to, since the rolls are covered with small cotton fibers and there is a tendency for the rolls to cling together, which prevents their feeding properly from dispensing devices in which such agitation is not provided.

I claim:

1. An article dispensing device, comprising a container having a dispensing opening therein, a closure member normally covering said opening, a plate mounted interiorly of a wall of said container opposite said opening, the lower end of said plate being curved outwardly toward said opening and having a portion thereof spaced inwardly from said opening a distance sufficient to receive an article to be dispensed forwardly thereof, and an operating lever having a portion thereof extending upwardly between said plate and said container wall opposite said opening, said lever being connected to said closure member to simultaneously remove said closure member from said opening and to move said plate toward said opening to eject an article positioned forwardly of said plate.

2. An article dispenser, comprising a container having a dispensing opening therein, a plate mounted interiorly of the wall opposite said opening, the lower end of said plate being curved downwardly and toward said opening, a metal plate having an upwardly bent portion positioned to engage the rear face of said curved plate, a horizontal portion of said plate being positioned to extend forwardly and having the forward portion thereof bent upwardly to close said dispensing opening, and operating means connected to said plate to simultaneously lower said vertical forward portion to uncover said dispensing opening and to move said rear portion forwardly to move said plate to discharge an article positioned forwardly thereof through said dispensing opening.
